CLAIM

The ornamental design for a lower body drying tool, as shown and described.

DESCRIPTION

FIG. 1 is a perspective view of a lower body drying tool, showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a perspective view of the lower body drying tool, shown in an environment of use.

The broken lines showing a user in FIG. 8 depict environmental subject matter that forms no part of the claimed design.

1 Claim, 4 Drawing Sheets
